UNITED STATES PATENT OFFICE.

FREDERICK STROBEL, OF MARION, OHIO, ASSIGNOR TO THE MARION MANUFACTURING COMPANY, OF SAME PLACE.

STRAW-CARRIER.

SPECIFICATION forming part of Letters Patent No. 396,345, dated January 15, 1889.

Application filed June 30, 1888. Serial No. 278,623. (No model.)

To all whom it may concern:

Be it known that I, FREDERICK STROBEL, a citizen of the United States, and a resident of Marion, in the county of Marion and State of Ohio, have invented certain new and useful Improvements in Straw-Carriers; and I do hereby declare that the following is a full, clear, and exact description of the invention, which will enable others skilled in the art to 10 which it appertains to make and use the same.

This invention relates to straw-carriers.

The object is to produce a device which shall render the employment of the cog-wheels 15 unnecessary; furthermore, to provide means whereby the carrier is enabled to be swung from one point to another; furthermore, to provide means for operating the carrier-belt, and, finally, to produce a device which shall 20 be simple of construction, efficient and durable in use, and comparatively inexpensive of production.

With these objects in view the invention consists in the improved construction and 25 combination of parts of a straw-carrier, as will be hereinafter fully described in the specification, illustrated in the drawings, and pointed out in the claim.

Referring to the accompanying drawings, 30 in which like letters of reference denote corresponding parts, Figure 1 is a perspective view of the rear end of a thrashing-machine, showing the straw-carrier secured in operative position. Fig. 2 is a top plan view of the frame removed from the rear end of the thrashing-machine and of the mechanism for imparting motion to the carrier-belt. Fig. 3 is a side view of the same; and Fig. 4 is a transverse sectional view taken through line 35 $z z$ on Fig. 3, wherein the manner of pivoting the frame to the projecting frame of the thrashing-machine is disclosed.

Reference being had by letter, A designates the rear end of a thrashing-machine, to which 45 is rigidly secured the frame B, upon the rear ends of which is journaled the drive-shaft C for operating the device. This shaft is provided upon its intermediate portion with a chain-pulley, D, and upon one end with the belt-pulley E, which is operated from the fan-shaft or any other shaft of the thrashing-ma-

chine by a belt, F. Journaled in bearings in one of the cross-pieces G of the rigidly-secured frame is a vertical shaft, H, having at each end a chain-pulley, I, one above and the other below the cross-piece. 55

J indicates the track, which is secured to the side pieces and the rear cross-piece of the stationary frame.

K designates the pivoted frame, which consists of the pieces K', K², K³, K⁴, and K⁵, the latter of which has the ends of the other pieces, which are bent, secured to it. The pieces K', K², and K⁴ are provided at their forward free or disconnected ends with blocks L, the faces 60 of which are recessed, as shown at K⁷, and nearly surround the vertical shaft, so that they may turn in any direction and yet be securely retained in position. When the pivoted frame turns, the lower edge of the piece 65 K⁵ slides upon the track, hereinbefore referred to.

Two bearing-arms, K⁶, project from the side of the piece K³, and in which are journaled the short shafts of two chain-pulleys, M, rotating in a horizontal plane, the same as the chain-pulleys of the short vertical shaft, while the piece K⁵ has projecting upward therefrom bearing-arms N for the shaft O, which has keyed to it the flanged pulleys P and the supporting-pulley P'. An endless chain passes around the chain-pulley D of the main drive-shaft C and over the chain-pulley secured to the lower end of the short vertical shaft, thus imparting motion to that shaft. 70 Another endless chain, Q, passes around the upper chain-pulley of the said short vertical shaft, around the forward chain-pulley of the piece K³, thence around a chain-pulley, R, secured upon the end of the shaft O, and, finally, 75 around the rear chain-pulley journaled upon the said piece K⁵. The lower end of the carrier-frame T is pivoted to the shaft O by means of the curved arms U, which are bolted to the said carrier-frame, so that the carrier 80 may be drawn up against the rear end of the thrasher by the ropes V or any other well-known means. The carrier-belt W passes around the carrier-frame in the usual manner, and then around the flanged pulleys, 85 which impart motion to the carrier-belt. As the straw is discharged from the thrasher, it 90

95 100

falls in the carrier, and the belt conveys it to the top and discharges it.

From the foregoing description, taken in connection with the accompanying drawings, 5 the operation and advantages of the invention will be readily understood without requiring an extended explanation. It will be seen that by forming the pulleys P of the shaft O with flanges they will prevent the carrier-belt from slipping laterally, which would naturally interfere with the operation of the carrier-belt.

Having thus described my invention, I claim and desire to secure by Letters Patent of the 5 United States—

The combination, with a frame projecting from the rear end of the thrashing-machine and a short vertical shaft journaled in the forward end thereof, of the pivoted frame having its forward-projecting pieces provided with recessed blocks for engaging the said shaft, substantially as set forth. 20

In testimony that I claim the foregoing as my own I have hereunto affixed my signature in presence of two witnesses.

FREDERICK STROBEL.
